US00D792440S

(12) **United States Design Patent** (10) Patent No.: **US D792,440 S**
Butcher et al. (45) Date of Patent: ** Jul. 18, 2017

(54) **DISPLAY SCREEN OR PORTION THEREOF WITH GRAPHICAL USER INTERFACE**

(71) Applicant: **Apple Inc.**, Cupertino, CA (US)

(72) Inventors: **Gary Butcher**, San Jose, CA (US);
Imran Chaudhri, San Francisco, CA (US); **Alan C. Dye**, San Francisco, CA (US); **Christopher Foss**, San Francisco, CA (US); **Aurelio Guzmán**, San Jose, CA (US); **Jonathan P. Ive**, San Francisco, CA (US); **Britt Nelson**, San Francisco, CA (US)

(73) Assignee: **Apple Inc.**, Cupertino, CA (US)

(**) Term: **15 Years**

(21) Appl. No.: **29/586,549**

(22) Filed: **Dec. 5, 2016**

Related U.S. Application Data

(63) Continuation of application No. 29/569,507, filed on Jun. 28, 2016, now Pat. No. Des. 773,527, which is a continuation of application No. 29/501,107, filed on Sep. 1, 2014, now Pat. No. Des. 760,759.

(57)

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
